UNITED STATES PATENT OFFICE

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE

RAILWAY-CAR CONSTRUCTION

Application filed April 9, 1928. Serial No. 268,598.

This invention relates to a railway car construction wherein the coupler is supported by a carrier which is swingably supported by links to the striking casting or other car part, such, for instance, as is shown in Gilpin Patent No. 1,658,120 of February 7, 1928.

It has been found advantageous to provide T-heads or trunnions on one or both ends of the supporting links because if a pin construction is used it must be retained by a nut or cotter or other similar means, which become loose or lost, thus making it possible for the link to become disengaged from either the car part or the carrier.

My device is an improvement upon such structures and comprises means to retain one or both of the links in operative position, that is, to retain the trunnions in their proper bearings which means are actuated and retained in their normal position by gravity alone and which may be easily moved out of the normal position to permit the removal of the T-head from its bearing, which means are preferably permanently attached to a part of the car.

In the drawings:

Fig. 1 shows a plan view on the right half of the center line and on the left hand of the center line a section on line 1—1 of Fig. 2.

Fig. 2 shows a typical application of my device to a railway car.

Fig. 3 is a section on line 3—3 of Fig. 1.

Figs. 4 and 5 show fragmentary portions of the car part, link and retainer.

Fig. 6 is a perspective view of the retainer shown in Figs. 4 and 5.

Figs. 7 and 8 are fragmentary portions of the car part, link and modified retainer.

Fig. 9 is a perspective view of the link shown in Figs. 7 and 8.

In the form illustrated the carrier 2 is swingably suspended from the striking casting (or car part 3) by links 4 at its opposite ends, which links are provided with T-heads or trunnions 5 at each opposite end which engage bearings in a carrier and car part, respectively.

The clearance 6 between the top of the coupler shank 7 and lower portion 8 of the striking casting, or in other words, the ver-

tical permissible rise of the coupler shank, is $\frac{3}{4}$ " as determined by the A. R. A., therefore, it is preferable to make the bearings in the carrier and car part, respectively, of a greater depth, or say about 1", so that the links cannot become disengaged from their bearings while the coupler is in position upon the carrier. If the journals for the trunnions are made less than $\frac{3}{4}$ " it is possible for the trunnions to jump out of the bearings due to impacts of the cars in service, particularly when being coupled, and if the vertical depth of the bearing is made greater than the said $\frac{3}{4}$ ", then the trunnions cannot be removed from the bearings while the coupler is in operative position on the carrier.

It is sometimes desirable to remove the carrier 2 or one of the links 4 while the coupler is in position upon the carrier, therefore, it is necessary to make the bearing (10) of at least one of the upper trunnions of less vertical dimension than the permissible vertical movement of the coupler (6), in which case some means must be provided to retain the trunnion in its bearing.

In my construction I provide such a means by retainer 11 having an elongated slot 12 therein which engages a pintle 13 permanently secured to the striking casting or other part of the car. When in normal position, which it assumes by gravity, the lower end of this retainer is adjacent the trunnion 5 so as to retain it in its bearing but with the pintle and slot arrangement it is capable of being moved in a vertical direction to permit the removal of the link from its bearing. The pintle 13 is provided with a head 16 and the lower portion of the retainer engages a recess 17 in the car part so that the head and the recess jointly and severally prevent the retainer from swinging in a plane laterally of the car. The retainer is of such width that it can not swing longitudinally of the car to an extent which would permit the removal of the link from its bearing. In the form illustrated, the walls 18 and 19 restrict this longitudinal swinging movement. From the above it will be seen that the retainer is prevented from swinging in any direction. When it is desired to remove the link from its

bearing a tool is placed within the slot 20 under the retainer and the retainer is moved vertically out of the way.

Figs. 7, 8 and 9 show a modified construction wherein the pivot 30 of the retainer is positioned normal to the construction shown in Figs. 4, 5 and 6. The lip 31 on the retainer 32 prevents it from swinging out of vertical line.

10 The accompanying drawings illustrate the preferred form of the invention, though it is to be understood that the invention is not limited to the exact details of construction shown and described, as it is obvious that various modifications thereof within the scope 15 of the claim will occur to persons skilled in the art.

I claim:

20 The combination in a railway car of a car part, a carrier swingably suspended therefrom by links, one of said links having a journal at its upper end engaging a bearing in the car part, a retainer secured to the car part so as to normally retain the journal in 25 its bearing, said retainer having a slot therein engaging a pintle on the car part whereby vertical movement of the retainer is permitted, and means to prevent the retainer from swinging in any direction.
